UNITED STATES PATENT OFFICE.

ROY D. FOULKE, OF WARSAW, INDIANA, ASSIGNOR TO WINIFRED DE PUY, OF WARSAW, INDIANA.

SURGICAL APPLIANCE.

Application filed September 18, 1922. Serial No. 588,805.

This invention relates to improvements in surgical appliances of that class wherein means are provided for sustaining broken bones in their normal position after having been readjusted. The objects of the improvement are: First, to provide means applicable to a patient afflicted with fracture of the clavicle bone which will afford facility in the reduction of the fractured 10 members to their normal position; and second, to afford a comfortable shackle for sustaining patient's body within such limitations as will prevent displacement of reduced fracture of the clavicle bone.

15 The objects of the invention are accomplished by the construction illustrated in the accompanying drawings, in which:

Fig. 1 is a rear elevation of the appliance shown applied to a patient;

20 Fig. 2 is a rear elevation of one of the posterior supports with portions thereof broken away and showing the interior construction; and

Fig. 3 is a side elevation projected from 25 Fig. 2, a portion being broken away.

The characters appearing in the description refer to parts shown in the drawings and designated thereon by corresponding characters.

30 The invention is comprised of a pair of posterior supports 1, the one being the counterpart of the other, and having non-elastic straps 2 for limiting the same from spreading apart.

35 Each support consists of a splint 3, preferably a flat metallic plate, to each end of which is hinged a buckle 4 and along one side of which, adjacent each end, is hinged a buckle 5. The splint having the buckles 40 attached thereto is riveted to a thick felt pad 6. The assembly composed of the splint and pad is encased within a leather pocket 7 provided with slits 8 through which the buckles 4 and 5 protrude respectively to the exterior of the pocket.

In connection with each support is provided an anterior support 9 consisting of a tubular leather casing 10 with a filling 11 of hair. In the ends of the anterior support 50 are respectively secured straps 12 that have connection with the buckles 4 of the corresponding posterior support.

The posterior supports are connected together by means of the straps 2 previously

referred to, the straps having connection at 55 their respective ends with the corresponding buckles 5 on said supports.

The straps 2 and 12 are preferably composed of non-elastic flexible bands so that the several parts of the appliance which are 60 held together by the bands will thereby be held within definite limitation from spreading relatively apart.

In utilizing the appliance, as in a case of clavicle fracture, the posterior supports are 65 positioned upon the scapula, while the patient is in a standing or sitting posture. The anterior supports are then buckled into connection with the corresponding posterior supports. Generally, in cases of clavical 70 fracture, the shoulder slips forward, downward and inward, and to rectify such dislocation it is necessary to move the shoulder, upward, outward and backward, and when so set it is also necessary to sustain 75 the fractured members securely in the position of their readjustment until their union is naturally effected. By manipulating the straps 2 and 12 in connection with the supporting members the patient's body may be 80 drawn into such position as to cause the fractured members to reassume their natural position to which they will be restricted for the required period of time necessary 85 for recovery.

The metallic splints 3 afford rigidity to the posterior supports, the pads 6 ease the pressure of the splints upon the back of the patient, and the leather pockets 7 and casings 10 admit of the preservation of a 90 sanitary condition of the appliance.

What I claim is:

In a clavicle splint of the class described, a pair of pads, brace members within said pads, auxiliary pads connected to the main pads and adapted to extend around and under the arms of the patient whereby said main pads will be positioned upon the scapulas of the patient, and adjustable connections secured to the main pads at points 95 spaced from their adjacent inner edges whereby said main pads may be drawn together and rocked and the shoulders of the patient drawn backwardly.

In testimony whereof I affix my signature.

ROY D. FOULKE.
